UNITED STATES PATENT OFFICE.

CONRAD M. CONRADSON, OF GREEN BAY, WISCONSIN.

ROTARY PUMP.

Application filed March 6, 1926. Serial No. 92,749.

This invention relates to pumps of that class in which one or more cylinders is arranged in a rotating member, the cylinders being provided with pistons to which a variable stroke is imparted by an offset centrally disposed crank pin.

One of the objects of the invention is to provide a pump of the class named which shall be simple in construction, powerful and efficient in operation, and in which direct and effective means are provided for counteracting the stresses incident to the operation of the pump.

Other objects and advantages will appear hereinafter.

The invention is exemplified in the combination and arrangement of parts shown in the accompanying drawings and described in the following specification, and it is more particularly pointed out in the appended claims.

In the drawings—

Fig. 1 is a longitudinal section through a pump illustrating one form of the present invention;

Fig. 2 is a transverse section substantially on line 2—2 of Fig. 1;

Fig. 3 is a section on line 3—3 of Fig. 1, showing the eccentric for the crank pin in one position of adjustment;

Fig. 4 is a section on line 3—3 of Fig. 1, showing the eccentric in a different position of adjustment;

Fig. 5 is an end view looking from the right in Fig. 1, with parts broken away;

Fig. 6 is a section on line 6—6 of Fig. 1, looking in the direction of the arrows;

Fig. 7 is a section on line 6—6 of Fig. 1, looking in the direction opposite the arrows;

Fig. 8 is a section on line 8—8 of Fig. 5;

Fig. 9 is a section on line 9—9 of Fig. 5; and

Fig. 10 is a section on line 10—10 of Fig. 5.

The pump mechanism is enclosed in a hollow spherical casing 15 having a detachable end plate 16 held in place by cap screws 17 at one end of the casing and a smaller end plate 18 held in place by cap screws 19 for closing the opposite end of the casing. A cylinder-carrying member 20 is arranged within the casing 15 and is supported at one end on bearings 21 which rest upon a sleeve 22 projecting inwardly from a web 23 formed integral with the end plate 16. The cylinder-carrying member 20 is

provided with a detachable portion 25 held to the portion 20 by cap screws 26. The part 25 is provided with a cylindrical bearing portion 27 which is supported on the end plate 18 by a radial and thrust bearing 28. A sleeve 29 is interposed between the bearing cylinder 27 and the bearing 28 and is provided with a flange 30 disposed against the end face of the part 25. The part 25 is provided with a shaft 31 to which a suitable driving pulley, not shown, is attached. This shaft extends through a central opening in the plate 18 and is surrounded by packing 32. It is apparent that rotation of the shaft 31 will rotate the cylinder-carrying member 20 within the housing 15.

A shaft 34 has one end journaled in the sleeve 22 and has its opposite end supported in bearings 35 supported within the cylindrical bearing drum 27. A bearing 36 is interposed between the shaft 34 and the part 25 so that the stress between the shaft 34 and the cylinder-carrying member 20 is supported on the two bearings 21 and 36. The shaft 31 is provided with an eccentric portion 37 which fits a cylindrical opening in a slide block 38 arranged to slide in guide faces 39 in the crank pin 40. The crank pin 40 has a cylindrical outer surface and is free to move vertically, but is held against transverse movement by a plate 41 having ribs 42 which intermesh with ribs 43 on the end of the crank pin 40. The plate 41 is held from rotation by projections 44 which extend into slots formed in the end of the sleeve 27. Rotation of the shaft 34 will shift the axis of the crank pin 40 vertically, the crank pin being shown in central position in Figs. 1 and 2, and in extreme positions in Figs. 3 and 4. The shaft 34 is rotated by a worm 45 meshing with a worm wheel 46 secured to the end of the shaft. Various forms of control mechanism may be employed for rotating the shaft 45. Connecting rods 47 are provided with bearing faces 48 which rest upon the outer surface of the crank pin 40. The connecting rods 47 support pistons 49 in the cylinders 50 formed in the cylinder-carrying member 20. The pistons are carried on suitable swing joints, a ball support 51 being shown for this purpose in the drawings. The connecting rods 47 are held to the crank pin 40 by flanged rings 52. When the cylinder support 20 is rotated the connecting rods 47 will rotate upon the outer surface of the crank pin 40 and when

75

105

110

the crank pin is eccentrically disposed the pistons 49 will be reciprocated in their cylinders due to the eccentricity of the stationary crank pin 40. The amount of reciprocation is controlled by the position of the crank pin. When the crank pin is in central position, as shown in Figs. 1 and 2, there will be no reciprocation of the pistons and the reciprocation will be maximum when the crank pin is in either of the positions shown in Figs. 3 and 4. The amount of reciprocation may be varied through all values between these two extremes to regulate the quantity of material pumped by the apparatus. The direction of delivery will be reversed by changing the axis of the eccentric portion of the shaft 34 from one side to the other of the axis of the shaft.

Each of the cylinders 50 is provided with a port 53 communicating with the other end of the cylinder. The ports 53 open through the end face of the cylinder-carrying member 20 in spaced position, as shown in Fig. 6. In the embodiment shown in the drawings there are seven cylinders and correspondingly seven ports leading from these cylinders. The web 23 is provided with a valve face 54 disposed against the end face of the cylinder bearing member 20 through which the ports 53 open.

At each side of the end member 16 there is provided a nozzle 55 connecting with elongated ports 56 which open through the valve face 54, as shown in Fig. 7. It will be apparent that the upwardly moving cylinders at one side of the pump will be connected through the ports 53 and 56 with one of the nozzles 55 while the down moving cylinders at the opposite side of the pump will be connected through the ports at the other side of the pump with the opposite nozzle 55. When the crank pin 40 is offset upwardly the pistons at one side of the pump will be drawing in liquid through the connecting nozzle 45 while the pistons at the opposite side will be discharging liquid through the other nozzle. If the shaft 34 is rotated to reverse the position of the crank pin the direction of delivery of the pump will be reversed. The amount of delivery in either direction may be regulated by adjusting the eccentricity of the crank pin by rotating the shaft 34.

In order to compensate for the reaction of the valve surfaces, reaction pistons 57 are arranged in cylindrical openings in the cylinder-supporting member 20, there being one reaction piston provided for each cylinder in the form of pump illustrated in the drawings. The pistons 57 are subjected to the fluid under compression in the cylinders 50 by means of ducts 58 so that the pistons 57 will be actuated by the same pressure fluid as that to which the valve faces are subjected. The pistons 57 are so proportioned that they produce a somewhat

greater pressure than the reaction of the valve faces and thereby insure close contact between the valve faces. To insure suction in starting the pump each piston is provided with a spring 59, the pressure of which is added to the pressure of the fluid against the piston. It will be seen that the pistons bear against the flange 30 so that the thrust is transmitted through the bearing 28 to the outer casing of the pump.

U-leathers 60 are used for packing the pistons 49 in the cylinders 50 and these U-leathers are held in place by caps 61 threaded into the openings in the ends of the cylinders 50 and having skeleton flanges engaging the U-leathers. The outer case 15 is provided with an opening 62 at its top in registration with which the caps 61 may be moved. This makes it possible to replace the U-leathers without disassembling the pump. The interior of the case 15 is filled with oil and a plenum tank 63 may be attached to the case 15 to register with the opening 62, the tank being provided with a head of oil 64 to insure a supply for filling the case at all times. The pump is designed to operate in connection with a closed system in which the liquid used is the same as that contained in the casing 15. In a system of this kind relief valves may be employed for excess pressure and arranged to discharge directly into the casing of the pump. Since the plenum tank 63 is subjected to atmospheric pressure the liquid level in the tank will readily rise to accommodate any oil discharged through the relief valve into the pump casing. These valves are formed on the outer face of the end member 16, as shown at 65, and have discharge openings 66, as shown in Fig. 8, communicating directly through the end member 16 with the interior of the pump housing. The valves are contained in sleeves 67 formed integral with the wall 16 and having a recess 68 extending around the interior of each sleeve. The recesses 68 communicate through cored openings 69 with the nozzles 55. Hollow cylinders 70 are secured within the sleeves 67 by caps 71 and the valve openings 66 are closed by valves 72 carried by valve stems 73 which are operated by springs 74 disposed within the cylinders 70 and bearing against nuts 75 secured to the end of the valve stems 73. When the pressure within the nozzle 55 becomes sufficiently great to overcome the force of the spring 74 the valve 72 will open and discharge sufficient liquid into the pump housing to relieve the excess pressure.

Replenishing valves 76 are also formed on the end plate 16 and are connected with the nozzles 55 through cored openings 77 in a manner similar to the relief valves 65. The replenishing valves, as shown in Fig. 9, are closed by balls 78 which are held seated by

springs 79 and which open from the interior of the casing to the nozzles 55 to replenish any deficiency in the liquid in the system, from the liquid contained in the pump housing. The liquid in the plenum tank 63 will supply the liquid thus withdrawn from the pump housing.

I claim:

1. A pump comprising a rotary cylinder-carrying member, a crank pin about which said cylinder-carrying member rotates, pistons connected with said crank pin, a rotary shaft for supporting said crank pin, and means for shifting the axis of said crank pin when said shaft is rotated.

2. A pump comprising a rotary member having radially disposed cylinders therein, pistons arranged to reciprocate in said cylinders, a crank pin about which said cylinders rotate, connecting rods interposed between said cylinders and crank pin, a shaft having an eccentric portion engaging said crank pin, and means for rotating said shaft to shift the axis of said crank pin to regulate the stroke of said cylinders.

3. A pump comprising a rotary member having radially disposed cylinders therein, pistons in said cylinders, a crank pin about which said cylinders rotate, connecting rods interposed between said crank pin and cylinders, a shaft having an eccentric portion on which said crank pin is mounted, means for rotating said shaft to shift the axis of said crank pin, and means for guiding said crank pin for straight line movement transverse to the axis thereof.

4. A pump comprising a rotary cylinder-carrying member, a shaft having an eccentric portion about which said member rotates, a slide block mounted on said eccentric portion, and a crank pin having an elongated opening therein for receiving said block, said block being slidable in said elongated opening transverse to the axis of said shaft.

5. A pump comprising a rotary member having radial cylinders therein, pistons in said cylinders, a crank pin for said pistons about which said cylinders rotate, and means for shifting the position of said crank pin relative to the axis of rotation of said cylinders, said shifting means comprising a block mounted for sliding movement transverse to the axis of rotation of said cylinders in an elongated opening in said crank pin, an eccentric for moving said slide block, and means for constraining said crank pin to move in a direction transverse to the direction of movement of said slide block in said elongated opening.

6. A pump comprising a rotary member having radially disposed cylinders therein, pistons slidably mounted in said cylinders, a cylindrical crank pin about which said cylinders rotate, connecting rods interposed between said crank pin and pistons, a shaft

extending through said crank pin and having an eccentric portion thereon within said crank pin, a bearing member interposed between said crank pin and eccentric portion, said bearing member being fixed against movement relative to said crank pin in one direction transverse to the axis of rotation of said cylinders but free to move relative to said crank pin transverse to said first-named direction, and guides for constraining said crank pin to move in said first-named direction when said shaft is rotated to shift the position of said eccentric portion.

7. A pump comprising a stationary casing, a cylinder-carrying member mounted to rotate within said casing, a crank pin about which said cylinder-carrying member rotates, a shaft having an eccentric portion for shifting the position of said crank pin, and guiding connection between said crank pin and stationary casing for restricting said crank pin to straight line movement transverse to the axis of rotation of said cylinder-carrying member.

8. A pump comprising a stationary casing, a cylinder-carrying member mounted for rotation within said casing, a crank pin about which said cylinder carrying member rotates, said crank pin having guiding connection at one end thereof with said stationary casing for constraining said crank pin from rotation while permitting straight line movement thereof transverse to the axis of rotation of said cylinder-carrying member, and means for shifting said crank pin.

9. A pump comprising a stationary casing, a cylinder-carrying member mounted for rotation within said casing, a crank pin about which said cylinder-carrying member rotates, a shaft having an eccentric portion for shifting said crank pin, and a guide plate interposed between one end of said crank pin and said stationary casing, said guide plate having projections on opposite faces thereof for engaging said crank pin and casing, respectively, to hold said crank pin against rotation while permitting straight line movement thereof transverse to the axis of rotation of said cylinder-carrying member.

10. A pump comprising a stationary housing, a cylinder-carrying member mounted to rotate within said housing, a shaft coaxial with said cylinder-carrying member having one end thereof projecting from said housing, a crank pin mounted on said shaft within said housing, and means operated by said shaft to shift the axis of said crank pin transverse to the axis of rotation of said cylinder-carrying member.

11. A pump comprising a stationary housing, a member having cylinders therein mounted to rotate within said housing, a shaft co-axial with said member and having one end thereof projecting from said hous-

- ing, a crank pin mounted on said shaft, pistons in said cylinders, connecting rods interposed between said crank pin and pistons, means for holding said crank pin 5 against rotation while permitting movement thereof transverse to the axis of said shaft, and an eccentric member on said shaft for shifting said crank pin when said shaft is rotated.
- 10 12. A pump comprising a stationary housing, a member having radially disposed cylinders therein rotatably mounted within said housing, a shaft co-axial with said member and having one end thereof projecting from said housing, a crank pin mounted on said shaft, pistons disposed in said cylinders, connecting rods interposed between said pistons and crank pin and having sliding connection with the outer face of said 15 crank pin, said shaft having an eccentric portion registering with said crank pin, a block having an opening therein fitting said eccentric portion, said block being disposed in a transversely elongated opening in said crank pin to permit sliding movement of said block relative to said crank pin in one direction while restraining said block against movement relative to said crank pin in the direction transverse to the 20 direction of said sliding movement, and a plate interposed between one end of said crank pin and a fixed portion of said housing, said plate having a projection thereon for restraining said crank pin against rotation while permitting movement thereof 25 in a direction transverse to the sliding movement of said block in said crank pin.
13. A pump comprising a stationary housing, a cylinder-carrying member mounted to rotate in said housing, a crank pin about which said cylinder-carrying member rotates, pistons mounted in said cylinder-carrying member, connecting rods interposed between said pistons and crank pin, a shaft 30 for supporting said crank pin, and bearings interposed between said cylinder-carrying member and shaft adjacent opposite ends of said crank pin.
14. A pump comprising a rotary member, 35 an eccentric about which said member rotates, pumping mechanism interposed between said rotary member and eccentric, and bearings for said rotary member closely adjacent the ends of said eccentric.
15. A pump comprising a rotary member, 40 a shaft arranged co-axial with said member, an eccentric on said shaft, pumping mechanism interposed between said rotary member and eccentric and actuated by rotation of said member about said eccentric, and bearings interposed between said rotary member and shaft closely adjacent the ends of said eccentric.
16. A pump comprising a stationary housing, 45 a member journaled for rotation in said
- housing, a shaft arranged co-axial with said rotary member, an eccentric mounted on said shaft within said rotary member, pumping mechanism interposed between said eccentric and rotary member and actuated by the movement of said rotary member about said eccentric, and bearings interposed between said rotary member and shaft adjacent the ends of said eccentric for counteracting the force exerted between said rotary member and eccentric by said pumping mechanism. 50
17. A pump comprising a stationary housing, a cylinder-carrying member within said housing, a shaft arranged concentric with said cylinder-carrying member, pumping mechanism interposed between said shaft and rotary member, a sleeve on said housing surrounding said shaft, and a bearing interposed between said sleeve and said rotary member. 55
18. A pump comprising a stationary housing, a cylinder-carrying member mounted to rotate within said housing, a shaft arranged co-axial with said cylinder-carrying member, a sleeve fixed to said housing and surrounding said shaft, a bearing interposed between said sleeve and cylinder-carrying member, an eccentric mounted on said shaft, and pumping mechanism interposed between said eccentric and cylinder-carrying member. 60
19. A pump comprising a stationary housing, a cylinder-carrying member mounted for rotation within said housing, a shaft co-axial with said cylinder-carrying member and projecting through a bearing sleeve formed on said housing at one end thereof, the opposite end of said shaft being journaled in said cylinder-carrying member, pumping mechanism interposed between said shaft and cylinder-carrying member, and bearings interposed between said shaft and cylinder-carrying member for counteracting force exerted by said pumping mechanism on said shaft and cylinder-carrying member. 65
20. A pump comprising a stationary housing, a cylinder-carrying member mounted for rotation within said housing, a shaft arranged within said housing co-axial with said cylinder-carrying member, a sleeve formed on said housing in which said shaft is mounted at one end thereof, the opposite end of said shaft being journaled in said cylinder-carrying member, a crank pin mounted on said shaft within said housing, means for shifting the position of said crank pin transverse to the axis of said shaft when said shaft is rotated, pumping mechanism interposed between said crank pin and cylinder-carrying member, a bearing interposed between said cylinder-carrying member and sleeve at one end of said crank pin for transmitting force between said shaft and cylinder-carrying member through said sleeve, a bearing interposed between said cylinder- 70

- carrying member and shaft at the opposite end of said crank pin, and a bearing interposed between said cylinder-carrying member and stationary housing adjacent the end of said crank pin journaled in said cylinder-carrying member.
21. A pump comprising a stationary housing, a member having radially disposed cylinders therein mounted for rotation within said housing, a bearing for supporting said member within said housing adjacent one end of said housing, said member having a shaft projecting from said housing at the end thereof adjacent said bearing, a second shaft extending into said member and co-axial therewith, said second shaft projecting from said housing at the end thereof opposite said first-named shaft, and pumping mechanism supported on said second shaft and co-operating with the cylinders in said member.
22. A pump comprising a stationary housing, a member having radially disposed cylinders therein mounted for rotation in said housing, a bearing for supporting said member in said housing adjacent one end thereof, a drive shaft secured to said member and projecting from said housing at the end thereof adjacent said bearing, a control shaft co-axial with said member and projecting from said housing at the end thereof opposite said drive shaft, pump operating mechanism mounted on said control shaft and co-operating with the cylinders in said member, bearings interposed between said control shaft and rotary member for resisting forces incident to the operation of said pumping mechanism, and means on said control shaft for regulating said pumping mechanism when said control shaft is rotated.
23. A pump comprising a stationary housing, a member having radially disposed cylinders therein rotatably mounted in said housing, a bearing interposed between said member and housing adjacent one end of said housing, a drive shaft secured to said member and projecting from said housing at one end thereof, a control shaft having one end journaled in said member and having the other end extending from said housing at the end thereof opposite said drive shaft, an eccentric on said control shaft, a crank pin mounted on said eccentric, piston rods and pistons connecting said crank pin with said cylinders, bearings interposed between said control shaft and rotary member adjacent the ends of said crank pin, and means for rotating said control shaft to cause said eccentric to shift said crank pin transverse to the axis of rotation of said rotary member.
24. A pump comprising a member having radially disposed cylinders therein, a crank pin centrally disposed relative to said member, means for shifting said crank pin into 65 and out of concentric position relative to said member, means for relatively rotating said member and crank pin, pistons in said cylinders, connecting rods on which said pistons are mounted, said connecting rods 70 having bearing surfaces engaging the outer face of said crank pin, and rings having flanges engaging said connecting rods to retain said connecting rods in position on said crank pin.
25. A pump comprising a member having a cylinder therein, a piston in said cylinder, a packing ring surrounding said piston, and a closure for said cylinder removably secured to said cylinder and arranged to hold 80 said packing ring in place.
26. A pump comprising a member having a cylinder therein, a piston in said cylinder, a packing U-ring surrounding said cylinder, and a removable closure for one end of said cylinder, said closure having means thereon for engaging the inner portion of said U-ring to retain said U-ring in place in said cylinder.
27. A pump comprising a member having a cylinder therein, a piston within said cylinder, packing surrounding said piston, and a removable closure for one end of said cylinder, said closure having a skeleton flange thereon for engaging said packing to retain said packing in place in said cylinder.
28. A pump comprising a member having a cylinder therein, a piston in said cylinder, said cylinder having a recess surrounding said piston, a packing U-ring disposed in said recess about said cylinder, and a removable closure for one end of said cylinder having a flange thereon for engaging the interior of said U-ring to hold said U-ring in place in said recess, said flange having a skeleton portion to provide openings to register with port openings into said cylinder.
29. A pump comprising a housing, a member disposed within said housing having a cylinder therein, a piston in said cylinder, packing surrounding said piston, and a removable closure for one end of said cylinder to permit access to said packing, said housing having an opening therethrough arranged to register with said removable closure to permit access to said cylinder for re-packing the same.
30. A pump comprising a stationary housing, a rotary member mounted within said housing and having a radially disposed cylinder therein, a piston within said cylinder, packing surrounding said piston, and a removable closure for one end of said cylinder arranged to engage said packing to hold said packing in place, said housing having an opening therethrough arranged to register with said removable closure to

permit re-packing of said cylinder while said rotary member is in place in said housing.

31. A pump comprising a housing, a rotary member having a cylinder therein mounted within said housing, co-operating valve faces on said housing and rotary member, and means for exerting pressure on said rotary member to hold said valve faces 10 in close contact.

32. A pump comprising a housing, a member having cylinders therein rotatably mounted within said housing, said rotary member and housing having engaging valve 15 faces, ports connected with said cylinders and opening through said valve faces, and means connected with said cylinders to be actuated by pressure therefrom to exert pressure on said rotary member to hold said 20 valve faces in close contact.

33. A pump comprising a housing, a member having cylinders therein arranged to rotate within said housing, co-operating valve 25 faces on said member and housing, ports communicating with said cylinders and opening through said valve faces, and fluid pressure actuated means operating between said rotary member and housing for holding said valve faces in close contact.

34. A pump comprising a housing, a member having a cylinder therein mounted for rotation in said housing, said rotary member and housing having engaging valve faces, a port communicating with said cylinder and opening through the valve face 35 of said rotary member, and means arranged in registration with the opening of said port and actuated by fluid pressure from said cylinder for pressing said valve faces 40 into close contact.

35. A pump comprising a housing, a member having a cylinder therein mounted to rotate within said housing, said housing and member having engaging valve faces, said 45 member having a port therein communicating with said cylinder and opening through the valve face in said member, a piston movably mounted in said member, and an abutment for said piston held by said housing, said piston being actuated by fluid pressure from 50 said cylinder.

36. A pump comprising a housing, a member having a cylinder therein mounted for rotation within said housing, engaging valve 55 faces on said housing and member, said member having a port connecting said cylinder and valve faces, means actuated by fluid pressure from said cylinder for holding said valve faces in contact, and a spring 60 for augmenting said holding means.

37. A pump comprising a housing, a member having circumferentially distributed cylinders therein mounted for rotation within 65 said housing, engaging valve faces on said housing and member, said member

having ports connecting said cylinders with said valve faces, and pistons mounted in said member in registration with each of said ports for holding said valve faces in close contact, each of said pistons being actuated by fluid pressure from the cylinder which communicates with the port with which said cylinder is in registration.

38. A pump comprising a housing, a member having circumferentially distributed 70 cylinders therein mounted for rotation within said housing, engaging valve faces on said housing and member, said member having ports connecting said cylinders with said valve faces, pistons mounted in said member in registration with each of said ports for holding said valve faces in close contact, each of said pistons being actuated by fluid pressure from the cylinder which communicates with the port with which 75 said piston is in registration, and springs for augmenting the fluid pressure on said pistons.

39. A pump comprising a housing, a member mounted to rotate within said housing, said pump and member having engaging valve faces, means for exerting force on said member to hold said valve faces in contact, an abutment for said force exerting means, and a thrust bearing interposed between 80 said abutment and housing.

40. A pump comprising a stationary housing, a member mounted to rotate within said housing and having radially disposed cylinders therein, engaging valve faces on 100 said rotary member and housing, said rotary member having ports therein connecting said cylinders with said valve faces, pistons slidably mounted in said rotary member and connected with said cylinders to 105 be actuated by fluid pressure from said cylinders, springs for augmenting the fluid pressure on said pistons, an abutment member for said pistons, and a thrust bearing interposed between said pistons and 110 housing.

41. A pump comprising a circulatory system closed housing for said pump having space therein separate from said circulatory system, pumping mechanism disposed within said housing, and a plenum tank for maintaining a supply of oil within said housing, said tank having free communication with the space in said housing separate from said circulatory system so that a head of oil in 115 said tank will cause said space to be filled with oil.

42. A pump comprising a closed housing, pumping mechanism disposed within said housing, a plenum tank for maintaining a 120 supply of oil within said housing, and means for establishing communication between the interior of said housing and the circulatory system of said pumping mechanism.

43. A pump comprising a closed housing, 125

rotary pumping mechanism disposed within said housing and having a system of passages through which liquid is circulated by said pumping mechanism, and a valve for establishing communication between the interior of said housing and said circulation system.

44. A pump comprising a closed housing, rotary pumping mechanism disposed within said housing and having a system of passages through which liquid is circulated by said pumping mechanism, and a relief valve arranged to discharge into said housing.

45. A pump comprising a housing, pumping mechanism disposed within said housing and having a system of passages through which liquid is circulated by said mechanism, a relief valve connected with said circulation system and arranged to discharge into said housing, and a plenum tank for maintaining a supply of liquid in said housing.

46. A pump comprising a housing, pumping mechanism disposed within said housing and having a system of passages through which liquid is circulated by said mechanism, and a replenishing valve for transferring liquid from the interior of said housing to said circulation system.

47. A pump comprising a housing, pumping mechanism disposed within said housing and having a system of passages through which liquid is circulated by said mechanism, a replenishing valve arranged to open at a predetermined excess of pressure in said housing over the pressure in the portion of said system with which said valve is connected, and a plenum tank for maintaining a supply of liquid in said housing.

48. A pump comprising a closed housing, pumping mechanism disposed within said housing and having a system of passages through which liquid is circulated by said mechanism, a valve having an opening communicating between said circulation system and the interior of said housing, and a spring for closing said valve, said spring arranged to yield to a predetermined excess of pressure to permit liquid to flow from the interior of said housing to said circulation system.

49. A pump comprising a closed housing, pumping mechanism disposed within said housing and having a circulation system through which liquid is forced by said pumping mechanism, a pair of nozzles communicating with said circulation system, and relief and replenishing valves connected with said nozzles and communicating with the interior of said housing.

50. A pump comprising a closed housing, pumping mechanism disposed within said housing and having a circulation system through which liquid is forced by said pumping mechanism, relief and replenish-

ing valves communicating between the interior of said housing and said circulation system and arranged to open at predetermined excesses of pressure for permitting passage of liquid between the interior of said housing and said circulation system, and a plenum tank for maintaining a supply of liquid within said housing.

51. A pump having two communicating passages therein, pumping mechanism for circulating fluid through said passages, and means for adjusting said pumping mechanism to reverse the direction of flow through said passages.

52. A pump having two passages communicating therewith, piston and cylinder mechanism for circulating fluid through said passages, valves for alternately connecting said piston and cylinder mechanism with said passages, and means for regulating the operation of said piston and cylinder mechanism to reverse the direction of flow of liquid through said passages.

53. A pump having two passages communicating therewith, a member having cylinders formed therein, pistons co-operating with said cylinders, valves for connecting said cylinders with said passages, and an adjusting device for regulating the operation of said pistons to reverse the direction of flow of fluid through said passages.

54. A pump having two passages communicating therewith, a rotary member having radially disposed cylinders formed therein, pistons arranged to reciprocate in said cylinders, a crank pin for operating said cylinders when said member is rotated, valve mechanism for connecting said cylinders with said passages, and means for shifting the axis of said crank pin to regulate the amount of flow through said passages and to reverse the direction of said flow.

55. A pump having a closed casing and an exit passage, pumping mechanism within said casing for discharging liquid through said passage, and a relief valve communicating with said passage and arranged to discharge into said casing when excess pressure is present in said passage.

56. A pump having an intake passage communicating therewith, a replenishing valve communicating with said passage, and a supply reservoir connected with said valve, said valve being arranged to open to discharge liquid from said supply reservoir to said intake passage when the pressure in said supply reservoir exceeds the pressure in said intake passage by a predetermined amount.

57. A pump comprising a closed housing, pumping mechanism arranged within said housing, said housing having an intake passage communicating with said pump, and a valve interposed between said intake passage and the interior of said housing, said valve

being arranged to open to discharge liquid from the interior of said housing into said passage when the pressure in said housing exceeds the pressure in said intake passage 5 by a predetermined amount.

58. A pump having a passage communicating therewith, means for reversing said pump to reverse the direction of flow through said passage, a relief valve communicating with said passage, and a replenishing valve communicating with said passage. 10

59. A pump having a pair of passages communicating therewith, pumping mechanism for circulating liquid through said passages, means for reversing said pumping mechanism to reverse the direction of flow of liquid through said passages, and relief and replenishing valves connected with each 15 of said passages. 20

60. A pump having a pair of passages connected therewith, pumping mechanism for circulating liquid through said passages, means for reversing said pumping mechanism to reverse the direction of flow through 25

said passages, and relief valves connected with each of said passages.

61. A pump having a pair of passages connected therewith, pumping mechanism for circulating liquid through said passages, 30 means for reversing said pumping mechanism to reverse the direction of flow through said passages, and replenishing valves connected with each of said passages.

62. A pump comprising a closed housing 35 having passages therefrom, pumping mechanism arranged within said housing and communicating with said passages, means for reversing said pumping mechanism to reverse the direction of flow through said passages, relief and replenishing valves connecting each of said passages with the interior of said housing, and a plenum tank communicating with said housing for maintaining a supply of liquid therein. 40

In testimony whereof I have signed my name to this specification on this 3rd day of March, A. D. 1926. 45

CONARD M. CONRADSON.
